UNITED STATES PATENT OFFICE

2,448,521

EMERGENCY SIGNALING DEVICE

Martin Dwyer, Hewlett Bay Park, N.Y.

Application May 17, 1943; Serial No. 487,261

7 Claims. (Cl. 102—37.8)

1

This invention relates to signalling devices and more particularly to smoke or pyrotechnic signal devices adapted to be carried in emergency life rafts, boats or the like.

Increasing air transport over large bodies of water has made it extremely important that all crews operating such transports have in their emergency life rafts day and night-time signalling devices capable of expelling large volumes of colored smoke or light-emitting composition. The same situation exists with respect to ships and lifeboats.

One of the principal requirements of such devices or signals is that they remain absolutely watertight and moistureproof until they are used, irrespective of the weather conditions and other environment to which they are exposed prior to such use, because the ignitable contents of the devices must be dry or else they cannot be used effectively, if at all.

One of the principal features of the invention relates to novel container constructions for such devices that are of extremely rugged construction, that are absolutely water- and moisture-proof, i. e., hermetically sealed, and that are capable of keeping the ignitable contents dry even under the severest conditions so that the devices may be used whenever required in an emergency.

Another object of the invention is to produce devices of this character that will be comparatively simple in construction, cheap and easy to assemble.

Another object of the invention is to provide devices of the character described that will be self-contained, each including everything necessary for its operation in an emergency and which may be put into use without requiring any tools.

In the past, it has been common practice to design a smoke or pyrotechnic signal to fit on a detachable handle, and to include such a handle in a kit including several signals so that the signals could be affixed individually to the handle and held thereby a safe distance away from the user's hand while being fired, ignited or burned. This made it essential to include an extra piece of equipment, namely, a handle with each kit, and had the great disadvantage that, if the individual handle were lost overboard or elsewhere, it would become impossible to fire, ignite or burn the signals of the kit. In other words, the dependency of these kits upon a detachable handle was one of their principal weaknesses.

Another object of the present invention is to

2

provide signalling devices that may be safely fired, ignited, burned or otherwise used and which are independent entirely of each other and of any requirement for a detachable handle.

Another object is to provide devices which may be safely held in hand by the user during use without requiring any handle whatsoever.

Another object is the provision of signalling devices, each of which is a completely independent entity, so that the loss of one or more will have no effect whatsoever on the ability to use those remaining.

Still another object of the invention is to provide signalling devices each equipped with a convenient handle as a part thereof which, prior to need, is collapsed or so arranged in a position of non-use on the signal device as not to interfere with safe, easy and compact packing of the safety signal kit.

20 A further object is the provision of handle constructions in connection with such signalling devices that can be readily incorporated with or applied to existing types of signalling devices and which are cheap to manufacture and assemble with such devices, and which can be made with minimum requirements of materials and labor.

Another object is the provision of handle constructions in conjunction with signalling devices that may be quickly and conveniently put into operative position by the user.

To the accomplishment of the foregoing and such other objects as may hereafter appear, this invention consists in the novel construction and arrangement of parts hereinafter to be described and then sought to be defined in the appended claims, reference being had to the accompanying drawing forming a part hereof and which shows, merely for the purposes of illustrative disclosure, preferred embodiments of the invention, it being expressly understood, however, that various changes may be made in practice within the scope of the appended claims without digressing from the inventive idea.

In the drawing, in which similar reference characters denote corresponding parts,

Figure 1 is an elevational view of one form of signalling device embodying the invention;

Fig. 2 is a top plan view of the device of Fig. 1;

Fig. 3 is a vertical section taken along line 3—3 of Fig. 2 and viewed in the direction of the arrows;

Fig. 4 is a bottom plan view of the device of

Fig. 1;

Fig. 5 is a bottom plan view of a detail of the internal construction;

Fig. 6 is a sectional view taken along line 6—6 of Fig. 5 and viewed in the direction of the arrows;

Fig. 7 is a sectional view taken along line 7—7 of Fig. 5 and also viewed in the direction of the arrows;

Fig. 8 is a plan view of the top of an internal container carried in the device of Fig. 1;

Fig. 9 is a vertical section similar to that of Fig. 3 illustrating a modified form of construction;

Fig. 10 is a top plan view of another form of signalling device embodying the invention;

Fig. 11 is a vertical section of the device of Fig. 10 taken along line 11—11 of Fig. 10 and viewed in the direction of the arrows;

Fig. 12 is a fragmentary section similar to that of Fig. 11 illustrating a modification in the handle construction;

Fig. 13 is a fragmentary section similar to that of Fig. 11 illustrating a further modified form of container construction;

Fig. 14 is an elevational view of a signalling device equipped with yet another form of novel handle construction and in which the latter is shown in its packing, collapsed or non-use position;

Fig. 15 is a transverse section taken along lines 15—15 of Fig. 14 viewed in the direction of the arrows;

Fig. 16 is a similar section taken along lines 16—16 of Fig. 14, also viewed in the direction of the arrows;

Fig. 17 is a view similar to Fig. 14 but illustrating the handle extended into position of use for permitting firing, igniting or burning of the contents of the signalling device;

Figs. 18 and 19 are detailed views of a further modified form of handle construction; and

Fig. 20 is a fragmentary elevation of still another form of such construction.

Referring to the drawing and first to Figs. 1-8 inclusive, 10 denotes an external casing or container of metal or other suitable material. In the embodiment shown, this casing is of cylindrical form but it may be of any desired form. The casing is provided or formed with annular ribs 11 that serve to reinforce it. A member 12 (Figs. 3, 5, 6 and 7) of substantially cuplike form is admeasured to fit within the upper end of the container 10. The bottom 13 of this member is fluted or grooved at 14 and 14a to provide reinforcement therefor and is also stamped or cut along the lines 15 so that leglike members 16 can be bent downwardly from the bottom 13 to the position shown in Figs. 3 and 7, leaving openings or perforations 18 (Fig. 7) in the bottom 13 adjacent to its periphery. A central opening 19 is also provided in the bottom 13. The openings 19 and 18 serve to permit rapid escape of the products of combustion from the device. The member 12 forms a spider-like support member whose function will be presently explained.

A cover member 20 is provided for the member 12. This cover member 20 has a larger diameter than that of the container 10 and its overlapping edges 20a are beaded over together with the upper edges of the container 10 and the shell-like member 12 to form a double annular sealing bead or rib 21. This bead is very secure and is made moisture- and leak-proof in any well-known manner, as by the use of solder or the like.

The cover member 20 has a comparatively large

opening 22 that is normally sealed by a removable tear strip or member 23 secured over said opening in well-known manner as by soldering or the like. This tear strip 23, while removable, effectively and completely seals the opening 22 against moisture, water and gas until it is removed. A suitable ring 24 or other equivalent means is attached to the tear strip 23 to facilitate removal of the latter by the user without tools. It is merely necessary for the user to grasp the ring 24 and pull off the tear strip 23 to expose the opening 22.

The entire inner wall of the container or casing 10 may be coated with an insulating lining 10a of any suitable material that may be applied either by spraying, dipping or in any other suitable manner. This lining 10a preferably has heat insulating properties.

An inner container 29 of metal or other suitable material for holding the burning compound is provided. This container 29 is admeasured to extend into the space afforded by the downwardly-extending legs 16 of the member 12, being suitably spaced and insulated from the legs 16 and bottom 13 of member 12 by a spacing and insulating liner 30 which is of asbestos or other insulating material. The top 29a (Fig. 8) of the inner container 29 is provided with a plurality of smoke-escape passageways 31 through which the products of combustion of the material within container 29 may escape to the opening 19 and thence outwardly of container 10 through opening 22. Likewise and for similar purposes, the side wall or walls of container 29 have a plurality of similar openings 32 (Fig. 3) leading to an annular space 33 between the containers 10 and 29.

The top 29a of the inner container 29 also has another opening 34. This opening has upstanding legs 35 for a purpose to be presently described.

The inner container 29 is provided with a paper or other readily combustible liner 39 and is filled with a suitable smoke compound 40 capable of producing large volumes of smoke when burned that will be visible as a cloud even in high wind. The constituents of this smoke compound include a suitable dye for coloring the smoke as desired, a suitable burning agent to produce the smoke and suitable fuel so that a sustained volume of smoke will be produced when the compound is ignited. Any of the commercially known satisfactory smoke-producing compounds may be utilized. A suitable fuse 41 extends through the compound 40 and terminates in a match-head 42 or other suitable igniter that will light the fuse 41. The head 42 lies below the opening 34. This match-head 42 is surrounded by a protective member 44 which in turn extends upwardly through the opening 34 and is held suspended in said opening by suitable means such as a cotter pin 45 that extends transversely between the legs 35 at the opening. A suitable striker 46 engages the match-head 42. This striker 46 has a pull-cord or wire 47 attached thereto which extends through a suitable channel 44a in member 44 into the space 48 between the top 29a and the top 20 of the two containers. A suitable handle 49 is attached to the pull-cord or wire 47 and lies in said space 48 for convenient grasping by the user when tear strip 23 is removed. If desired, the cord 47 may be attached directly to the tear strip 23 so that its removal will automatically cause the striker 46 to ignite the match-head 42. The lower end of the fuse 41

is secured against withdrawal by the cross pin 50. This pin and the cotter pin 45 both are preferably of combustible material such as zinc or the like.

If the burning compound 40 is in solid form, i.e., a compressed solidified cylinder of the smoke-producing material, or a jellied substance, the liner 39 may be dispensed with, if desired.

A plug 51 of pressed clay, asbestos or other suitable material lies at the bottom of the compound 40 and serves to retain it in container 29. A suitable bottom 29b is provided for the container 29, being reentrant and attached suitably at 29c to said container. A sleeve or jacket 52 surrounds the inner container 25 for a part of its length near its lower end, filling the space between it and the outer container 10 and leaving an insulating air space 53 between the bottom 29b and the bottom 52a of the sleeve 52. This sleeve or jacket 52 is of suitable heat-insulating material such as asbestos and serves to help to heat-insulate the outer container 10 from the inner one, so that the outer container can, if desired, be grasped and held by the user during burning of the smoke compound 40. The liner or jacket 52 may be omitted and utilization may be made of the air in spaces 33 and 53 for the same purposes.

The bottom 54 of the container 10 completely closes the lower end of the latter and is suitably secured thereto by beading over the rim 54a of said bottom and the lower edge 10b of said container to form the watertight and moisture-proof hermetical sealing bead 55.

In assembly, of course, the containers 10 and 29 are both loaded from their bottom ends, the manner of assembly being to load container 29 with its contents 40, 41, 42 and 44, then to insert the plug 51 therein, then to apply the bottom 29b, then to insert the loaded container 29 into container 10 as shown in Fig. 3, then to apply the packing or jacket 52, then to apply the bottom cover 54 and then to form the sealing bead 55 so that the container 29 and its contents are completely sealed in leak-proof and waterproof manner within container 10, i.e., they are hermetically sealed within the outer container.

An auxiliary handle construction may be provided in order that the container 10 may be held further away from the user during burning of the smoke compound. In the embodiment shown in Fig. 3, a member 56 may be secured to the bottom 54 as by spot welding or in any other suitable way. Eyelets or hinges 57 are provided on the member 56 at suitably spaced-apart points. Rods or handle members 58 of bendable metal such as iron wire or any other suitable material are pivotally secured to the hinges or eyelets 57. These rods 58 are bent at 59 around the bead 55 so that in position of non-use they extend substantially parallel with and lie against the side wall or walls of the container 10. The rods or members 58 may be extended and bent over at 58a (Fig. 2) to hook over the annular bead 21 of container 10, and will thus be retained in their non-use position until released by the user. A frangible annular band (not shown) of "cellophane" tape, "Scotch" cellulose tape, or any other suitable binding tape serves, as an alternative, to secure the rods against the container 10 in their non-use position. When the device is to be used, the band or tape is destroyed. The rod members 58 may then be rotated about eyelets 57 to the dotted position of Fig. 1 at which time they extend below the bottom 42 and serve as a convenient handle for the con-

tainer that may be grasped by the user. One or more of such rods 58 can be used.

As an alternative for the fuse-igniting means shown in Fig. 3, that shown in Fig. 9 may be substituted without modification of any other parts of the construction. All parts having the same reference numerals are the same as those in Fig. 3. Instead of the parts 42, 44, 45, 47 and 49 of Fig. 2, the fuse 41a is provided at its upper end with a match-head 42a. The latter extends upwardly through opening 34a and is secured by a suitable crosspiece 60 of combustible material that extends between the legs 35a. A suitable protective cap member 61 overlies the match-head 42a resting on the top 29a. A cord or wire 62 secured both to the cap member 61 and to the bottom 43 of the spider member 12 permits withdrawal of the cap member through opening 22 when the tear strip 23 is removed, but prevents loss of said cap member. A striking surface 64 is provided on the cap member for igniting the match-head 42a. The tear strip 23 has a plate member 65 attached to its underside to engage the cap member and to prevent its displacement prior to use.

To use the devices of Figs. 3 and 9, if they are equipped with the handle members or rods 58, the hooked-over portions 58a are released from the bead 21 and the rods are rotated to the dotted position of Fig. 1. Thereafter, the ring 24 is grasped and the tear or pull strip 23 is removed. The handle 49 which is then exposed through opening 22 is then grasped and pulled to ignite the match-head 42 and light the fuse 41. Or else the cap member 61 is lifted to expose match-head 42a, reversed, and its striking surface 64 rubbed across the head 42a to ignite it and light fuse 41a. The burning of either fuse 41 or 41a ignites the compound 40 and such ignition burns away the paper container 39 covering holes 31 in the top 29a of inner container 29. It also burns away the pin 45 or member 60. The voluminous smoke produced by the burning smoke compound 40 escapes first through openings 31, 19 and 22 to atmosphere. As the burning of the compound 40 progresses downwardly within container 29, the paper liner or container 39 burns with it, exposing the side openings 32 in the walls of container 29 and permitting smoke from the burning compound to enter freely and voluminously into space 33. From the latter, the smoke passes freely through openings 18 in the member 12 and to atmosphere through opening 22, mingling there with the smoke coming from openings 31 and 19. The openings 32 serve both as smoke outlets and as safety outlets should undue pressure arise in casing 29 during combustion.

Numerous other structural modifications are, of course, possible. An additional modification is shown in Figs. 10 and 11. Therein 100 denotes an external casing or container of metal or other suitable material. In the embodiment shown, this casing is of cylindrical form but it may be of any desired shape. The top 111 of the container 100 comprises a cup-like shell member 112 admeasured to fit within the upper end of container 100. A portion 113 of the bottom of the shell member is made reentrant for a purpose to be presently described. An opening 114 of comparatively large diameter is provided in the upper wall of the reentrant portion 113 to permit rapid escape of the products of combustion in the device. Likewise, and for similar purposes, a plurality of openings 115 are provided in the bottom of the shell member 112.

A cover member 116 is provided for the shell member 112. This cover member 116 has a larger diameter than that of the container 100 and its overlapping edges 116a are beaded over together with the upper edges of the container 100 and shell member 112 to form a double annular sealing bead or rib 117. This bead is very secure and made moisture- and leakproof in any well-known manner as by the use of solder or the like.

The cover member 116 has a large opening 118 that is normally sealed by a removable tear strip or member 119 secured over the said opening 118 in well-known manner as by soldering or the like. This tear strip 119, while removable, effectively and completely seals the opening 118 against moisture and water until it is removed. A suitable ring 120 or other equivalent means is attached to the tear strip 119 to facilitate removal of the latter by the user without tools. It is merely necessary for the user to grasp the ring 120 and pull off the tear strip 119 to expose the opening 118.

The entire inner wall of the container or casing 100 may be coated with an insulating lining 100a of any suitable material that may be applied by either spraying, dipping or in any other suitable manner. This lining preferably has heat-insulating properties.

An inner container 125 of metal or other suitable material for holding the burning compound is provided. This container 125 is admeasured to extend into the reentrant portion 113 of the shell member 112, being suitably spaced and insulated from the walls of the latter by a spacing and insulating liner 126 which is of asbestos or other insulating material. The insulating liner is optional, as the air space between container walls filled by such liner could serve itself as the heat insulation if desired. The top of the inner container 125 is provided with a plurality of smoke-escape passageways 127 through which the products of combustion of the material within container 125 may escape to the opening 114 and thence outwardly of container 100 through opening 118. Likewise, and for similar purposes, the side wall or walls of container 125 have a plurality of similar openings 128 leading to the annular space 129 between the containers 100 and 125.

The inner container 125 also has another opening 130 in its top. This opening has an upstanding annular rim 131. A removable closure cap 132 is mounted on the rim 131. This cap is provided with a striking surface 133 or any other equivalent igniter for igniting the smoke-producing compound, as will be presently described.

The inner container 125 is provided with a paper or other readily combustible liner 135 and is filled with a suitable smoke compound 136 capable of producing large volumes of smoke when burned that will be visible as a cloud even in high wind. The constituents of this smoke compound include a suitable dye for coloring the smoke as desired, a suitable burning agent to produce the smoke, and suitable fuel so that a sustained volume of smoke will be produced when the compound is ignited. Any of the commercially known satisfactory smoke-producing compounds may be utilized. A suitable fuse 137 extends through the compound 136 and terminates in a match-head 138 or other suitable igniter that will light the fuse 137. The head 138 lies below cap 132. The igniters of Fig. 2 or 9 could be used for fuse 137 if desired.

If the burning compound is in solid form, i. e.,

a compressed solidified cylinder of the smoke-producing material, or a jellied substance, the liner 135 may be dispensed with, if desired.

A plug 140 of pressed clay, asbestos or other suitable material forms the bottom of inner container 125 and serves to retain the contents 136 therein. A sleeve or jacket 141 surrounds the inner container 125 for a part of its length near its lower end, filling the space between it and the outer container 100 as well as the space between the plug 140 and the bottom 142 of the container 100. This sleeve or jacket 141 is of suitable heat-insulating material such as asbestos and serves to heat-insulate the outer container 100 from the inner one, so that the outer container can, if desired, be grasped and held by the user during burning of the smoke compound 136. This sleeve is optional.

The bottom 142 of the container 100 completely closes the lower end of the latter and is suitably secured thereto by beading over the rim 142a of said bottom and the lower edge 100b of said container to form the watertight and moisture-proof hermetical sealing bead 42.

In assembly, of course, the containers 100 and 125 are both loaded from their bottom ends, the manner of assembly being to load container 125 with its contents 135, 136, 137 and 138, then to insert the plug 140 therein, then to insert the loaded container into container 100 as shown in Fig. 11, then to apply the packing or jacket 141, then to apply the bottom cover 142 and then to form the sealing bead 143 so that the container 125 and its contents are completely sealed in leak-proof and waterproof manner within container 100, i. e., they are hermetically sealed within the outer container.

An auxiliary handle construction may be provided in order that the container 100 may be held further away from the user during burning of the smoke compound. In the embodiment shown in Fig. 11, a member 150 may be secured to the bottom 142 as by spot welding or in any other suitable way. Eyelets or hinges 151 are provided on the member 150 at suitably spaced-apart points. Rods or members 152 of bendable metal such as iron wire or any other suitable material are pivotally secured to the hinges or eyelets 151. These rods 152 are bent at 153 around the bead 143 so that in position of non-use they extend substantially parallel with and lie against the side wall or walls of the container 100. A frangible annular band 154 of regenerated cellulose tape, or any other suitable binding tape serves to secure the rods against the container 100 in this non-use position. When the device is to be used, the band or tape 154 is destroyed. The rod members 152 may then be rotated about eyelets 151 to the dotted position of Fig. 11, at which time they extend below the bottom 142 and serve as a convenient handle for the container that may be grasped by the user.

As an alternative for the frangible tape, the rods or members 152 may be extended and bent over at 152a (Fig. 12) to hook over the annular bead 117 of container 110, and will thus be retained in their non-use position until released by the user.

As an alternative for the pull-strip 119 of Figs. 10 and 11, the cover member 116 may be modified to that shown in Fig. 13. In the latter figure, the cover member 116m has an upstanding annular rim 160 about opening 118m. This rim is threaded suitably and a screw cap 161 is removably supported on the threaded rim. A

suitable packing gasket 162 is provided so that a water and moisture-proof seal may be obtained between the cap and the rim to effectively seal the contents of container 100. Other standard forms of containers could be used with any of the modifications disclosed. Certainly, the one of Figs. 2 and 9 could replace those of Figs. 10 to 20, if desired.

To use the device, if it is equipped with the handle members or rods 152, the frangible band 154 is broken (or the hooked-over portion 152a released from the bead 117), and the rods are rotated to the dotted position of Fig. 11. Thereafter, the ring 120 is grasped and the pull strip 119 is removed, or else cap 161 (Fig. 13) is removed. The inner cap 132 which is then exposed through openings 118 or 118m is then lifted from rim 131, exposing the match-head 138. The cap 132 is reversed and its striker surface 133 rubbed across the match-head to ignite the latter and 20 light the fuse 137. The burning of fuse 137 ignites the compound 136, and such ignition burns away the paper container 135 covering holes 21 in the top of inner container 125. The voluminous smoke produced by the burning smoke compound 136 escapes first through openings 121, 114 and 118 to atmosphere. As the burning of the compound 136 progresses downwardly in container 125, the paper liner or container 135 burns with it, exposing the side openings 128 in the 30 walls of container 125 and permitting smoke from the burning compound to enter freely and voluminously into space 129. From the latter, the smoke passes freely through openings 115 in the shell member 112 and to atmosphere through opening 118, mingling there with the smoke coming from openings 127 and 114. The openings 128 serve both as smoke outlets and as safety outlets should undue pressure arise in casing 125 during combustion.

Since inner casing 125 is heat-insulated from the outer casing 100 by the liner 126, the jacket 141, and the insulating lining 100a, the container 100 may be quite safely grasped near its lower end during combustion of the contents 136. The handle members 152 are, therefore, adjuncts which, while convenient, are not absolutely necessary for safe operation.

The construction and arrangement of parts produces a very rugged, moisture- and waterproof signalling device that will withstand rough treatment, moist or wet climatic conditions, or even actual submersion in water and will be ready for instant use in an emergency.

Other handle constructions that may be used with the signalling device are shown in Figs. 14 to 20 inclusive.

Referring to these figures and first to Figs. 14 to 17 inclusive, 170 denotes the container or casing of a signalling device which may be any desired type of signalling device.

The handle construction is adapted to be permanently associated with the container and furthermore to be so positioned thereon that prior to use it is in a condition or so-called collapsed, position of non-use which adds no material bulk to the container so that most economical packing of devices into kits can be effected. In the embodiment shown, a ring or annular band member 172 is mounted securely on the container adjacent to its bottom end. This ring or band 172 is of suitable metal such as iron or steel or any other metal or material such as heat-resisting plastic or fire-retarding and waterproofed composition. Eyelets 173 having axially-extending openings 174

are provided in the surface of the band, preferably, by stamping and offsetting portions of the band wall. A substantially axially-extending element or rod 175 is slidably supported in each eyelet opening 174. A headed portion 176 is provided at one end of each rod. A bent-over portion 177 is provided at the opposite end of each element or rod and serves as an abutment member to prevent complete withdrawal of the rod from its supporting eyelet when the rod is moved in one direction. The rods are preferably admeasured to be substantially equal in length to the distance between the upper and lower flanges 170a, 170b, at opposite ends of the container, and when assembled with the container 170 are placed in the position shown in Fig. 14, i. e., extending along and substantially in parallelism with the container sides between its opposite ends.

A frangible retaining band or member 178 serves conveniently to maintain the elements or rods against the sides of the container 170 in the position shown in Fig. 14. The band 178 may be of any suitable material, for example, it may be of regenerated cellulose tape, any other type of self-adhesive tape, or other binding tape to bind the elements to the side surfaces of the container. The main requirement is that this tape securely hold the rods 175 in the non-use position of Fig. 14 until the device is to be used, and that it be resistant to destruction during handling prior to use. It may be of easily-destructible wire. It should also be capable of being quickly removable or destructible by the user without requiring tools of any kind, since the latter may not be available when the device is needed.

To use the device, it is necessary for the user simply to remove or destroy the retaining band 178 and move the rods or elements to the use position. To do this, the rods or elements 175 are slid in the eyelets 173 to the dotted position of Fig. 17 until their bent-over portions 177 engage or abut the eyelets 173. They are then bent around the flange 170b and inwardly towards each other below the container end to the full line position of Fig. 17. All of them may then be grasped by one hand of the user. So arranged, they provide a rigid handle for supporting the container in adequately-spaced, safe position from the hand of the user. The contents of the container 170 may then be ignited or fired and safely burned.

The rods or members 175 are preferably of bendable metal such as iron wire or of any other suitable bendable material. They, as well as ring member 172, may be coated with heat-resistant and heat-insulating material if necessary, should they have a tendency to become overheated during use of the device, to avoid burning the user's hand by heat conduction. The ring members 172, 172a, 172b may have a heat-insulating lining (not shown) between their inner surfaces and the surface of the container 170.

The members 175 need not be circular in cross section. They may, for example, be flat strips 175a, shown in Figs. 18 and 19. In such event, the eyelets 173a in ring 172a will have openings 174a modified in shape to accommodate such strips rather than rods. In such event, the ends 177a of said strips can be enlarged in any suitable way to prevent complete withdrawal of said strips 175a through their eyelets 173a as, for example, shown in Fig. 19.

Likewise, the members 175 need not be mounted slidably in the eyelets 173. Instead, member 175b (Fig. 20) may be pivotally supported at 175c

from the eyelets 173b of band 172b and swung from a non-use position like that in Fig. 14 and bent to the use position shown in dotted lines in Fig. 20 upon removal of or breaking of the band 178.

While plural handle members are disclosed in connection with the various modifications, in some instances a single handle member is sufficient and can be used in place of such plural members.

Other modifications in construction are possible without departing from the spirit of the invention and are contemplated. There is no intention of limitation to the exact details shown and described.

What is claimed is:

1. In a signalling device adapted to be held in hand during use, an outer container, an inner container for smoke producing compound or the like, means for hermetically sealing said inner container and its contents within said outer container, a cup-like spacing member secured to said outer casing and extending into it, said cup-like member having an opening in its bottom, means extending downwardly from said bottom to center an end of said inner container relative to said outer container, a heat insulating liner lying between portions of said inner container at one end and said downwardly extending means, a jacket of insulating material surrounding said inner container for a part of its length near its other end, said downwardly extending means of said spacing member, said heat insulating liner and said jacket serving to maintain said liner container spaced from said outer container and heat insulated therefrom, said outer container having an opening, a removable closure member normally hermetically closing said last-named opening, said inner container having escape openings to permit easy and voluminous escape therethrough to said last-named opening of smoke developed by said smoke producing compound upon its being burned within said inner container after removal of said closure member from said last-named opening, and means within said outer container for igniting said smoke producing compound access to which is made available upon removal of said closure member.

2. In a signalling device adapted to be held in hand during use, an outer container, an inner container for smoke producing compound or the like, a cup-like shell member secured to one end of said outer container and extending into the latter, said shell member having a reentrant portion into which an end of said inner container extends and being provided with openings to permit free and voluminous escape therethrough of smoke developed by said smoke producing compound upon its being burned within said inner container, a heat insulating liner in said reentrant portion, a covering member closing said first-named end of said outer container, means providing a hermetic seal between said covering member, said container and said shell member, said covering member having an opening, a removable member normally hermetically closing said last-named opening, a second covering member closing the opposite end of said outer container and means forming a hermetic seal between said second covering member and said outer container whereby the contents of said outer container are hermetically sealed therein.

3. In a signalling device adapted to be held in hand during use, an outer container, an inner container for smoke producing compound or

the like, a cup-like shell member secured to one end of said outer container and extending into the latter, said shell member having a reentrant portion into which an end of said inner container extends, and being provided with openings to permit free and voluminous escape therethrough of smoke developed by said smoke producing compound upon its being burned within said inner container, and said inner container having similar openings communicating with said first-named openings, igniting means for said smoke burning compound, a liner for heat insulating said inner container from said shell member, a heat insulating jacket surrounding the inner container for a portion of its length near its other end, a covering member closing said first-named end of said outer container, means providing a hermetic seal between said covering member, said container and said shell member, said covering member having an opening, a removable closure member, normally hermetically closing said last-named opening, a second covering member closing the opposite end of said outer container and means forming a hermetic seal between said second covering member and said outer container whereby the contents of said inner container are hermetically sealed within said outer container.

4. In a signalling device adapted to be held in hand during use, an outer container, an inner container for smoke producing compound or the like, a cuplike member adjacent one end of said outer container, leg members extending from said cuplike member serving to position an end of said inner container within said outer container and to center it to provide an annular space between said two containers, said cuplike member having openings overlying the annular space and an opening overlying the said end of said inner container to permit free and voluminous escape therethrough of smoke developed by said smoke producing compound upon its being burned within said inner container, a covering member closing said first-named end of said outer container, means providing a hermetic seal between said covering member, said outer container and said cuplike member, said covering member having an opening, a removable member normally hermetically closing said last-named opening, a second covering member closing the opposite end of said outer container, and means forming a hermetic seal between said second covering member and said outer container whereby the contents of said outer container are hermetically sealed therein.

5. In a device of the character described, an outer container, an inner container for smoke producing compound or the like, a cuplike member adjacent one end of said outer container, leg members extending from said cuplike member serving to position an end of said inner container within said outer container and to center it to provide an annular space between said two containers, said cuplike member having openings overlying the said annular space and an opening overlying the said end of said inner container to permit free and voluminous escape therethrough of smoke developed by said smoke producing compound upon its being burned within said inner container, a covering member closing said first-named end of said outer container, means providing a hermetic seal between said covering member, said outer container and said cuplike member, said covering member having an opening, a removable member normally hermetically closing said last-named opening, a second cover-

ing member closing the opposite end of said outer container, jacket means for heat insulating said inner and outer container from each other, and means forming a hermetic seal between said second covering member and said outer container whereby the contents of said outer container are hermetically sealed therein and whereby said outer container may be held in hand by the user during burning of the contents of said inner container.

6. In a signalling device adapted to be held in hand during use, a metallic outer container, a metallic inner container for smoke producing compound or the like, a cuplike member extending into said outer container from one end thereof, said cup-like member having a central opening in its bottom, means extending downwardly from said bottom to serve for centering an end of said inner container and for providing an annular space between the latter and said outer container, and said cup-like member having additional openings overlying said annular space, a metallic covering member closing said first-named end of said outer container, said covering member, said cup-like member and said first-named end of said outer container being joined together and hermetically sealed at their joint, said covering member having an opening, a removable metallic tear strip positioned over said last-named opening and removably joined to said covering member to provide a hermetic seal about said last-named opening, means for removing said tear strip, a fuse extending through the compound in said inner container, an igniter for said fuse, a protective cover for said igniter, a striker for said igniter operable after removal of said tear strip, a heat insulating liner lying between said downwardly extending means, said bottom of said cup-like member and portions of said inner container, a heat insulating jacket surrounding said inner container for a part of its length adjacent its other end, a covering member closing the other end of the outer container, and means forming an hermetic seal between said last-named covering member and said outer container, whereby the contents of said outer container are hermetically sealed therein.

7. In a signalling device adapted to be held in hand during use, a metallic outer container, a metallic inner container for smoke producing compound or the like, a cup-like member extending into said outer container from one end thereof, said cup-like member having a central opening in its bottom, leg members bent downwardly from said bottom to serve for centering an end of said inner container and for providing an annular space between the latter and said outer container, said cup-like member having additional openings

5 in its bottom overlying said annular space to permit free and voluminous escape therethrough of smoke developed by said smoke producing compound upon its being burned within said inner container, a fuse extending through the compound, a match head igniter for said fuse, a protective member overlying said match head, said protective member having a striker surface, means for securing said protective member 10 against loss, a metallic covering member closing said first-named end of said outer container, said metallic covering member, said cup-like member and said first-named end of said outer container being hermetically joined together, said metallic 15 covering member having an opening, a removable metallic tear strip positioned over said last-named opening and removably joined to said metallic covering member to provide a hermetic seal about said last-named opening, means for 20 removing said tear strip, means attached to said tear strip for engagement with said protective member to prevent displacement of the latter, a heat insulating liner lying between said leg members, said bottom of said cup-like member 25 and portions of said inner container, a heat insulating jacket surrounding said inner container for a part of its length adjacent its other end, a covering member closing the other end of the outer container, and means forming an hermetic 30 seal between said last-named covering member and said outer container, whereby the contents of said outer container are hermetically sealed therein.

MARTIN DWYER.
